US00D861027S

(12) **United States Design Patent** (10) Patent No.: **US D861,027 S**
 Anzures et al. (45) Date of Patent: ** Sep. 24, 2019

(54) **DISPLAY SCREEN OR PORTION THEREOF WITH GRAPHICAL USER INTERFACE**

- (71) Applicant: **Apple Inc.**, Cupertino, CA (US)
- (72) Inventors: **Freddy Anzures**, San Francisco, CA (US); **Imran Chaudhri**, San Francisco, CA (US); **Alan C. Dye**, San Francisco, CA (US); **Bradley William Griffin**, Redwood City, CA (US); **Jonathan P. Ive**, San Francisco, CA (US); **Tiffany Jon**, Sunnyvale, CA (US); **Nicholas V. King**, San Jose, CA (US); **Stephen O. Lemay**, Palo Alto, CA (US); **Hoan K. Pham**, San Jose, CA (US); **Wan Si Wan**, Sunnyvale, CA (US); **Christopher Wilson**, San Francisco, CA (US); **Giancarlo Yerkes**, Menlo Park, CA (US)
- (73) Assignee: **Apple Inc.**, Cupertino, CA (US)
- (**) Term: **15 Years**
- (21) Appl. No.: **29/658,298**
- (22) Filed: **Jul. 30, 2018**

Related U.S. Application Data

- (63) Continuation of application No. 29/619,798, filed on Oct. 2, 2017, now Pat. No. Des. 824,412, which is a continuation of application No. 29/567,725, filed on Jun. 11, 2016, now Pat. No. Des. 798,893.
